TELEPHONE PHONOGRAPHIC MEANS OF COMMUNICATION

Filed Sept. 22, 1928

UNITED STATES PATENT OFFICE

GEORGE R. COOPER, OF UPPER DARBY TOWNSHIP, DELAWARE COUNTY,
PENNSYLVANIA

TELEPHONE-PHONOGRAPHIC MEANS OF COMMUNICATION

Application filed September 22, 1928. Serial No. 309,196.

This invention relates to improvements in sound recording apparatus and has for its object the provision of a simple, efficient and inexpensive device for automatically and electrically reproducing records of telephonic conversation and the present application is a companion to my contemporaneously pending application Serial No. 307,712.

Another object of this invention is to provide an improved mechanism designed to automatically and electrically convey a message across a telephone as soon as a party calling is connected by the central operator. Thus if one party is calling another over the phone and the second party is absent a message will be communicated audibly to the caller, communicating the fact that the party called is not in, and directing the caller to deliver his message into the transmitter in order that his message may be electrically recorded upon a phonograph in the office or home of the party called.

A still further object of this invention is to provide a device containing economical sound recording mechanism located in an office, home or the like, which operates, in the act of a party calling speaking into his telephone transmitter. In thus calling a party on the wire, the message transmitted by the party calling into the phone, will be suitably and instantly recorded accurately. When the party returns who has been absent, he can readily listen to and recover the message that has been recorded during his absence.

The present invention is also effective to record a conversation had over the telephone between the party calling and the party called, without the party calling knowing that his message is being recorded for instant recovery. This becomes important often times when it is desired to have a record of a telephone communication in proving the making of a contract and the like in court.

This invention consists of parts that are so combined and arranged as to assure the restoration to normalcy of all circuit connections affected by message recording mechanism.

With the above and other objects in view my invention consists of the combination, ar-

rangement and details of construction disclosed in the drawings and specification, and then more particularly pointed out in the appended claims.

In the drawings, wherein similar reference characters designate similar parts throughout the respective views,

Figure 1 is a side elevation, partly in section, of the parts of my invention,

Figure 2 is a fragmental detail view of a message stop device,

Figure 3 is a sectional elevation, partly in end elevation,

Figure 4 is a detail elevation of a solenoid used in conjunction with my invention,

Figure 5 is a detail elevation of a solenoid used in conjunction with my invention,

Figure 6 is a detail elevation of a device for returning the apparatus to normal when a caller "hangs up" the receiver of his telephone before receiving entire message from wax cylinder 40.

Referring to the drawings which are merely illustrative of my invention 10 designates the base of the telephone instrument located in any local station or place, and 11 is the box housing the parts of the telephone signal apparatus. A receiver 13 is removably hung upon a switch arm 12, the usual transmitter 14 also being provided.

A designates the telephone bells in the box 11, and B designates the clapper for sounding the bells, when a call is being made. The clapper B is carried by an oscillating bar D having a center of movement at C, while a rod E movably connected to the bar D is pivotally connected at its upper end, to a movable armature 83; F designates the casing containing the parts for operating the receiver and transmitter. Terminals 15 and 16 extend from this casing F as follows: a wire 17 runs from terminal 16 to an electro-magnet 18 from which runs another wire 19 to the main telephone line; another wire 26 runs from terminal 15 to the main telephone line. A wire 21b is connected from terminal 16 to a wire 27 which connects with a contact 84 mounted on a bolt 25 secured in the box 11. Wire 27 connects to a wire 28 which runs to one side of the bat-

tery 29, a wire 30 running from the other side of this battery to a contact post 31 mounted upon the base of an electrical motor 35, there being another post 32 on this motor from which runs a wire 64', which connects with a contact post 65a located at the upper end of the box 11. Post 65a connects through knife switch 61—W with armature 23—83 which contacts with bolt 25. The motor 35 has a shaft 36 upon a pulley 36a, on which pulley is trained a belt 37 which is also trained upon a pulley 38 fixed upon a countershaft 39 suitably mounted in a standard 37. At each end of the shaft 39 is a phonographic cylinder designated respectively 40 and 40a. Over the cylinder 40 is mounted a plurality of longitudinally separated hook members or contacts 41 having preferably integral collars 44 slidably and adjustably mounted upon a rod 42 positioned by means of the legs 43, screws 45 being employed to lock these sleeves in any desired position.

Associated with the wax cylinder 40 is a recorder-reproducer 46 having a support 47 which is operatively mounted slidably and adjustably upon the rod 51 of a balanced bracket or teeter 51. Support 47 is engaged by a spring 50 coiled around the rod 51, this spring also bearing against an adjustable stop 97 having a fastening latch or set screw 98.

The needles of styluses 60 and 60d are carried by recorder-reproducers 46 and 46a respectively.

A balanced bracket or teeter, similar to the one already described, is associated for use in conjunction with the other wax cylinder 40a, and it is counterbalanced by the first named cylinder. Each bracket or teeter is designed to be vertically movable, being guided in such movement by the collars 59 formed upon the ends of fixed arms 57a and 57b of standard 57. The brackets or teeters are respectively formed centrally at their upper planes with suspended arms 52 and 52' having elongated slots 53 and 53' into which project pins 54 and 54' which are mounted upon the teeter 55 pivoted centrally at 56 to the standard 57.

61 designates a handle of a make and break switch consisting of contacts W and 65c. The switch 61 makes contact with a knife member W connected to the armature 23. The switch, so far as the present invention is concerned is made to control the making and breaking of a circuit having electrical connections secured to contact W and contact 65c. A contact post 66 is secured to the upper end of box 11 and from it runs a wire 68 to a contact 80 which is secured to a conductive rod 79 adjustably mounted within an arm 72 formed upon a bracket which is insulatedly mounted upon a sleeve 70 of magnetic power, which sleeve

is carried in embraced relation by the solenoid 69; the sleeve itself being supported in erect position by means of the post or pedestal 88. There is a separate solenoid with mountings associated with each phonograph 40 and 40a, the parts being somewhat similar. Wire 68c (see Fig. 5) connects contact 73 with the solenoid 69. A wire 74f runs from this solenoid 69a to the wire 74d to make and break contact member 74c mounted upon, in insulated relation, a standard 57. This contact 74c is pressed against by contact 74b mounted upon and insulated from rod 80c. (See Fig. 3).

Wire 74e runs from contact 74b to wires 74e and 74r to contact 74p which is insulated from plunger 76r, circuit then continues through shoe 85, slide rod 87, wire 74m, wire 74, battery 29, wires 28 and 28d, post 66d, armature 23, contact 67, wire 68, binding post 80, conductor 79 and contact arm 72.

When one spider moves up the other moves down by virtue of the pendulum or teeter 55. Assuming that the machine is in its normal position, as shown in Figure 1. The phone bell rings and the telephone circuit to recorder-reproducers 46 and 46a are closed and the motor circuit is also closed and the caller is receiving a message from cylinder 40. When the message is over and the roller contact operatively carried by the needle carrier 46 contacts one of the hook contacts 41, which has a contact with rod 42, joined by the wire 74a, electrical circuit is closed to solenoid 69a as follows: from 74a' to solenoid 69a, through wire 68b to binding post 73a, to the arm 72a, through the conductive rod 79a, binding post 80a, wire 69c, battery 29, wire 28, wire 27, post 84, contact 25, armature 23—83, switch 61, post 65a, wire 21c, wire 89, binding post 48; thence roller 96, hook 41, post or arm 42, wires 74a and 74d, contacts 74e and 74b, wire 74e, back to the wire 74a'.

Plunger 76a has now been electrically attracted by solenoid 69a, has moved downward and the circuit is broken by the insulation 78a entering arm 72a, but spider 51a is held steady in its present position by the action of brakeshoe 85a pressing against plunger 76a. Shoe 85 is mounted terminably upon a slide rod 87 a coiled spring being interposed between holder 84 for rod 87. A telephone-receiver transmitter 77 is mounted at the upper end of the standard 57, being preferably hung upon an armature 80c by the link or hanger 78; at the end of this armature is a binding post 82 from which runs a wire 21c to wire 28 which runs to one side of battery 29.

As the recorder-reproducer for the wax cylinder 40 moves either to reproduce sounds or to record the same, while the wax cylinder is rotating, the support 47 of the recorder-reproducer moves against the spring 50, compressing it; this continues until one of the hook contacts 41 is reached. Secured to

needle carrier 46 is a latch lever 93 which is fulcrumed to swing upon a pivot 92 on the carrier; the free end of the lever carries a roller 96 while its opposite end 94 is slidably secured to a retractable spring 95; this spring normally disposes the roller just low enough in advance of the needle 60 to pass over hook contact 41 and latch thereagainst as this needle reaches the end of its sweep having traversed a predetermined distance intervening between the adjacent end of the wax cylinder and the first hook contact 41. It is necessary to latch this needle to prevent spring 50 which is compressed as the needle moves longitudinally from pushing the needle back and thus scratching the record cylinder, and also to allow the electrical contact effected by the contact roller 96 and hook contact 41 to be of sufficient duration of time. 20 When the needle nears the particular hook contact 41 the roller 96 in advance of it will automatically, as the needle continues to move upon the cylinder, engage and move over the ridge of this hook contact so that the needle 5 engages one side of this hook contact 41 while the latter roller engages the other side thereof; the contact of needle 60 with hook contact 41 closes a circuit to solenoid 69a.

In operation when it is desired to record 30 messages of varying character upon the cylinder 40, which is for transmitting messages over the phone to parties calling while a person is absent, the person talks into the transmitting instrument 77, the particular message 35 it is desired to record upon this cylinder. See that the switch W is open and the switch 65c closed.

Place the receiver transmitter or needle carrier 46 on the correct section of the cylinder 40 by lifting lever or frame 55, adjusting the stops 98 and 46h, and then lowering frame 55 to place the needle 60 upon the record cylinder 40. Take the receiver transmitter 77 off the hook 79 of the contact lever 60b to allow the former to spring up automatically against the contact 81 to close the motor circuit. As frame 55 is lowered the armature plunger 51d is also lowered and is held down in this position by the pressure of the 40 spring pressed brake shoe 85, attached to the solenoid 69a. The motor circuit is closed as follows: contact 81 to binding post 34 to wire 33 through motor to wire 30, to battery 29, through wire 28 and 21e to binding post 82, contact 80b and back to contact 81. The operator then speaks a message through receiver-transmitter instrument 46, such as follows:—

“Hello, Blank and Company speaking. The office is closed now as our hours are from 9 a. m. to 4.30 p. m. If you cannot call up in the morning, please dictate and leave your message.”

The person then calling receives this mes-

sage when central telephone station establishes the connections properly.

Suppose it is now desired to receive and answer a call while the owner is away from his office. When the exchange operator is 20 making a connection over the phone, the telephone bell clapper B moves vibrantly, depressing rod E and causing armature switch 83 to be moved downwardly against spring 24, so as to contact electromagnet 18, 25 which is energized at this point so as to hold the armature switch 83 in engagement and contact with contact post 25. The talking circuit is closed while talking is in progress, as follows: telephone line wire 19 is connected to electromagnet 18; from this magnet wire 17 runs, and connects through wire 21b to wire 27 which is connected to contact post 25, engaged by armature switch 83, which, when switch W is closed (as it should be when the office is closed) is in circuit with contact 65a; wire 21c runs from contact 65a and connects through wire 89 with binding post 48 of the receiver transmitter 46; and from the other binding post 49 runs a wire 90 connecting through wires 21 and 21p, armature 23, wire 21g to the other telephone line wire 26 of the talking circuit. It will be seen that the transmitter 14 and receiver 13 of the distant circuit is included in the talking circuit through wires 19 and 26. This energizes the receiver transmitter instrument 46. The circuit to motor 35 has also been closed as follows: from contact 65a, through knife switch W, through armature 83, contact post 25, wires 27 and 28 to one side of battery 29, and from the other side of the battery runs a wire 30 to the motor 35, and a wire 64' runs back from this motor 35 to the contact 65a. The motor thus starts 100 running and turns both cylinders 40 and 40a.

When the owner left his office for home he closed the switch 61, lowered down manually the spider plunger 51d in the solenoid 110 69, to place the needle 60 on the appropriate message section of the record 40; the brake shoe 85, which bears against plunger 76a holds the plunger and both cylinders 115 steadily in position. So when the motor circuit is closed the receiver transmitter 46 having already been energized, the cylinder 40 begins to turn, and the needle 60 begins to trace the record inscribed or indented on cylinder 40 and the result is that the caller 120 hears the message intended to be conveyed during the absence of the party called.

As receiver transmitter 46 continues to move the message is being heard by the caller, until the roller 96 of the lever 93 125 which travels with this instrument rolls over the raised edge of the next adjacent hook contact 41, at which time the needle abuts this contact immovably, as the spring 95 is compressed enough to allow the roller 130

96 to roll over contact 41. This action takes place against the compression of spring 50 which is coiled around the rod 51. The receiver transmitter is now at rest having delivered a message from the station number one of the recording cylinder 40. In a similar manner the next station record between contacts first and second designated 41, may be delivered by moving adjustable stops 97, 10 46h to the right positions to assure that the needle will traverse the proper part of the record.

When the needle 60 comes to a stop after having delivered the proper message, it contacts the hook contact 41; this closes the electrical circuit to the electro-magnet or solenoid 69a, (see Fig. 1 and Fig. 4) as follows: from hook contact 41 to rod 42, wires 74a and 74d, contacts 74c and 74b, wires 74e and 74a' 15 to the solenoid 69a; from this solenoid runs wire 68b to the binding post 73a; when the armature plunger 76a is in upper position, as it is while the message is being delivered from cylinder 40, the conductor portion 79a makes 20 electrical contact with binding screw 73a, which is insulated from body 70a; and by means of wire 69c connected to the conductor portion 79a of armature plunger 76a, current flows to one side of battery 29; from the other 25 side of this battery current flows through wire 28, wire 27, binding post 84, contact 25, armature 83, switch W, contact 65a, and thence runs a wire 21c to wire 89, through binding post 48 to needle 60 and roller 96, thus completing the circuit. When solenoid is thus 30 energized armature plunger 76a is drawn down being held in this position by the brake shoe 85 which yieldably allows this plunger to move downward. In this position the non-conducting portion 78a of armature plunger 76a breaks the electrical contact between binding post 73a and conductor 79a which 35 breaks the solenoid circuit instantly.

As armature plunger 76a moves downwardly urged by the solenoid 69a the needle or stylus 60a is brought into contact with cylinder 40a, and the caller may now register a message upon the wax cylinder 40a. As the spider 51a is lowered the pendulum 55 swings 40 to raise spider 51 and with it the receiver transmitter instrument 46 out of engagement with the wax cylinder 40. In this manner the message delivering circuit is open, while the message recording circuit is closed and 45 recorder-reproducer 46 has been moved to a position superimposed over its initial position by action of spring 50.

When the person calling has delivered his message and has hung up the phone the circuit 50 to the receiver transmitter 46 at the right of Fig. 1 is disrupted or broken as follows: due to hanging up the distant receiver, the central exchange operator breaks the circuit connections through main telephone wires 19, 55 26 and thus electrical magnet 18 is deener-

gized, which causes the armature 23-83 under influence of spring 24, to fly upwardly into contacting engagement with 67 and 67d, and to move out of engagement with binding post 25 and with contacts on ends of wires 21p and 21q. It will be noted that this portion of the armature 23-83 is insulated from the right section thereof by insulation 82. When the armature has thus moved, the circuit is closed to the other solenoid at the left of Fig. 1, as follows: current flows from one side of battery 29 through wires 28 and 28d, to binding post contact 66d, thence the current flows through contact 67d, armature 23-83, through contact 67, binding post 66, 70 then by wire 68 (see Fig. 5) to binding post 80 and conducting portion 79 of the plunger 76; thence through arm 72, wire 68c and solenoid 69 and out through wire 74f, 74d, contacts 74e and 74b of circuit breaker wires 74e, 74r, contact 74q (see Fig. 4), shoe 85, 75 stem 87, wires 74m and 74, and then back to the other side of the battery. As a result, the solenoid 69 thus energized draws plunger 76 downwardly in turn causing spider 51 to 80 lower, and placing needle 60 in contact with message transmitting wax cylinder 40, brake shoe 85 holding plunger 76a up and therefore plunger 76 down by action of balance rod pendulum 55. The spring 50, in conjunction 85 with the above action had previously readjusted the receiver transmitter 46 to its initial normal position for conveying the very next message, as it is evident that just as soon as spider 51a goes down spider 51 comes up, 90 causing roller 96 to roll upwardly off contact strip 41, until, being free spring 50 shifts member 60 back to normal position. Spider bracket 51a has moved upwardly as 95 the pendulum 55 has swung to lower spider 51, and needle 60a of the receiver transmitter 100 at the right of Fig. 1 is out of contact with the adjacent cylinder.

Should the caller hang up when needle carrier 46 is part way through a message 110 on cylinder 40, armature 23 flies upwardly and energizes a circuit to solenoid 69a as follows:

Stop 46h contains a binding post 46g which electrically connects with contact 46f. 115 When needle 60 has started a message on the way, carrier 46 moves to the right allowing spring 46i to pull contact 46j against contact 46f thus establishing a circuit to solenoid 69a as follows: 69a, 68b, 73a, 72a, 79a, 120 80a, 69c, 30, 29, 28, 28d, 66d, 23, 66, 68, 46m, 46g, 46n, 46f, 46k, 43, 74a, 74d, 74c, 74b, 74e, 74a', back to 69a. Now 76a plunges 46 rises and is pushed back to normal by the spring 50, thereby disconnecting said circuit as 46j 125 and 46f are now separated. As the spider 51 is up, the solenoid 69 is automatically energized and the machine restored to normal. The stop 46h is also designed to prevent spring 50 from pushing needle carrier 46 130

past the point where speech starts, or off the message record.

Reproducing and recording needles may be interchanged in the record-reproducers.

5 Means in common use, with necessary modifications, will be employed to move recorder-reproducers on the cylinders.

Having described my invention, I claim:

In apparatus of the character described
10 the combination with a telephone circuit, a motor mechanism controlled by the closing of said telephone circuit, a record carrier operated by said motor mechanism, a sound reproducing device coacting with a record
15 on said carrier and connected in circuits with said telephone circuit, a second record carrier operated by said motor mechanism, a sound recording device cooperating with a record on said second named record car-
20 rier, said sound recording mechanism being in circuit with said telephone circuit, a magnetic mechanism controlled by said sound reproducing device for positioning said sound recording device in operative relation
25 to a record on said second named record holder, an electromagnetic mechanism controlled by said telephone circuit for positioning said sound reproducing device in opera-
30 tive relation with a record on said first named record holder.

In witness whereof he has hereunder set
his hand this 5th day of July, 1928.

GEORGE R. COOPER.
